Oscar M. Wolff Inventor

By L. V. Miller

Attorney

UNITED STATES PATENT OFFICE.

OSCAR M. WOLFF, OF CHICAGO, ILLINOIS.

REEL.

Application filed October 31, 1924. Serial No. 747,112.

To all whom it may concern:

Be it known that I, OSCAR M. WOLFF, a citizen of the United States, residing at Chicago, in the county of Cook and State 5 of Illinois, have invented certain new and useful Improvements in Reels, of which the following is a specification.

This invention relates to a reel which, while capable of being used in other relations is particularly adapted for holding sausage casings which are made up in the countries of origin in rings or skeins of different sizes. My improved reel is particularly adapted for holding these skeins 10 of different size and allowing them to be unwound therefrom without obstruction.

One feature of the reel is to construct it in varied diameters so that one of the sizes will fit the particular skein or ring being 15 unwound.

Another feature of the device is to so construct it that possibility of the casing getting under the reel and entangled in the mechanism is avoided.

Another feature of the device relates to the vertical adjustment of the reel to fit spindles of different types or to take up 20 wear.

Another feature of the device is the reduction in the number of parts and the consequent small cost of production of the reel.

With these and other objects which will appear as the description proceeds, I will describe one form of my invention as illustrated in the accompanying drawings in which:

Figure 1 is a sectional view of the reel.

Figure 2 is a view of the reel frame with the outside cover removed; and,

Figure 3 is a vertical view of the frame shown in Figure 2.

1 is the base of the reel which may be provided with a boss 2. I prefer to employ a separate spindle 3, although this spindle may be integral with the base, and insert it in a hole drilled in the boss 2.

A frame 4 comprises a base portion 5 and upstanding portions which are preferably shaped as shown in Figs. 1 and 2, these upstanding portions being connected at their tops by a portion 6 having a hole therethrough into which the spindle 3 projects. This hole may be screw-threaded at its top

and a screw 8 screwed thereinto. A ball 9 may rest in the hole between the screw 8 and the spindle 3, thus forming a ball bearing.

Over this frame 4 and snugly fitting around the same, I provide a cover 12 which I preferably make of different sizes, 55 the part 13 at the top being of one size, the part 14 just below the part 13 being of a larger size and the part 15 being still larger than the part 14. The diameter of the portion 13 may gradually increase as shown in 60 Fig. 1 until it reaches the diameter of the portion 14 and the diameter of this portion 14 may gradually increase as shown until it reaches the diameter of the portion 15. These portions 13, 14 and 15 being of different 65 diameters will take care of skeins of casings of different sizes in which they are ordinarily shipped from the countries of origin.

The bottom of the portion 14 is spread 70 out as shown at 16 and may have an upstanding flange 17 and this portion may fit into a hollowed out portion of the base 1, there being only a small space left between the flange 17 and a flange 18 on the base 1. 75 The object of this construction is to prevent the casings as they are unwound from getting under the cover 12 and thus obstruct the unreeling operation from the reel.

In case the spindle 3 is not sufficiently long the proper position of the frame 4 and cover 12 above the base 1 could be regulated by operating the screw 8.

It will thus be seen that I have provided 80 a reel having different diameters throughout its length to accommodate skeins of different diameters and a frame for carrying the outer covering of different diameters together with an adjustable ball spindle 85 bearing, the parts being so constructed that they can be easily taken apart and cleaned and are capable of manufacture in sections with little cost and when the reel is assembled, it turns easily and is provided with 90 means to prevent the casing from getting under the cover to cause trouble as they are being unwound.

I claim as my invention.

1. A reel comprising a base having a 100 hollowed out upper surface, an upstanding

spindle and a reel proper revoluble about the spindle, said reel being flared at its base and said flared portion fitting into the hollowed out portion of the base.

5. 2. A reel comprising a spindle, a hollowed out base, a reel proper having successively larger cylindrical portions to snugly fit skeins of sausage casings of different diameters, said reel also including conical portions intermediate the cylindrical portions and at its bottom snugly fitting inside the hollowed out base to prevent said casings passing between said reel and base.

15. 3. A reel comprising a spindle, a base, a frame having different diameters throughout its length revolvable thereon and having a hole in its upper portion, means adjustable in the hole for raising or lowering the frame, and a cover fitting around the frame and also having cylindrical portions with intermediate conical portions of different diameters, the portion having the smallest diameter being at the top.

25. 4. A reel comprising a base having an upstanding circular flange, a reel proper comprising a cover flared at its base to fit within the circular flange of the base, said reel being of different diameters from top to bot-

tom, and a spindle upstanding from said base and around which the reel revolves. 30

5. A reel comprising a base portion having an upstanding circular flange near its periphery and an upstanding spindle, a frame supported on the spindle at its top, and means for adjusting the height of the frame above the base, and a cover for the frame flared at its base and fitting within the upstanding circular flange thereon.

15. 6. A reel comprising a base, a spindle upstanding therefrom, a reel proper revolvable about the spindle and supported thereon and flared to a horizontal circular shelf at its base and means for adjusting the height of the reel proper above the base.

25. 7. A reel comprising a base, a spindle upstanding therefrom, a reel proper revolvable about the spindle and supported thereon and flared at its base to form a horizontal supporting shelf and a ball at the top of the spindle and a screw about the ball for adjusting the height of the reel proper above the base. 45

In testimony whereof I hereunto affix my signature.

OSCAR M. WOLFF.
